US00D327129S

United States Patent [19]

Casale et al.

[11] **Patent Number:** **Des. 327,129**[45] **Date of Patent:** **** Jun. 16, 1992**[54] **BUILDING**

[75] Inventors: **Frank R. Casale; Nicola D. Casale; Antonio A. Casale; Richard P. Bennett**, all of Albuquerque, N. Mex.

[73] Assignee: **Nunzio's Pizza, Inc.**, Beverly Hills, Calif.

[**] Term: **14 Years**

[21] Appl. No.: **358,182**

[22] Filed: **May 26, 1989**

[52] U.S. Cl. **D25/33; D25/1**

[58] Field of Search **D25/1, 6, 18, 23, 33**
